Term of patent 3½ years

(Cl. D81—19)

Fig. 1

Fig. 2

Fig. 1 is a perspective view of a space heater cabinet or similar article showing my new design. The side wall opposite that shown is substantially identical with that shown.

Fig. 2 is a fragmentary top plan view of the space heater cabinet or similar article shown in Fig. 1, illustrating the nature and appearance of the top louvers.

The dominant features of my new design are shown in solid lines in the drawing.

I claim:

The ornamental design for a space heater cabinet or similar article, as shown and described.
